X-RAY APPARATUS

Franz Zabransky, Vienna, Austria

Application February 26, 1948, Serial No. 11,111
In Austria December 7, 1945Section 1, Public Law 690, August 8, 1946
Patent expires December 7, 1965

9 Claims. (Cl. 323—45)

1

My invention relates to X-ray apparatus.

X-ray techniques are known to be set the task of making use of the highest admissible effect of the X-ray tube, which results in the most favourable conditions for operating from a therapeutical and diagnostical point of view. According to the present state of development of techniques this aim could be only attained if a transformer adjusted for full effect at each secondary voltage was used, which means a heavy weight of the high-voltage transformer due to its then necessary large dimensions. A unit constructed of the X-ray tube and the high-voltage transformer offers substantial advantages of construction (such as higher reliability of operation, better cooling of the X-ray tube, omission of the safety-high-voltage feeding-cables of large diameter), yet the weight of this X-ray unit is limited, the more so as for clinical use easy adjustment in any position is required.

It is an object of my invention to provide such an X-ray apparatus that the aforesaid movable unit in relation to a certain weight yields a higher effect than could be attained hitherto.

It is a further object of my invention to provide such an X-ray apparatus that the effect of the X-ray tube can be made full use of, and that the transformer combined with it always works with highest efficiency.

Still another object of my invention is to provide for an auxiliary transformer in local separation from the movable unit, which transformer is adapted to be adjusted for delivering various voltages to the X-ray tube. This offers a possibility of controlling the anode-voltage of the tube, while a comparatively small, movable unit, that operates with high economy and is well adapted to the requirements of medical practice, is retained.

Furthermore it is an object of my invention to provide an X-ray apparatus the tube of which is fed by way of a high-tension cable by a high-voltage transformer locally separated from it, whereat it is possible to operate the transformer always with highest efficiency which implies economic and technical advantages.

These and other objects will more clearly appear from the following detailed description of a preferred embodiment illustrated in the drawing which shows in a diagrammatical way the circuit according to which the invented apparatus operates.

In the drawing A denotes the X-ray unit connected with the control-board B. The X-ray unit A consists of the tube 1, the filament trans-

former 2, and the high-voltage transformer with the primary windings 3 and the secondary windings 4, 5. In the control-board B there are arranged an additional adjustable transformer 5 consisting of the primary winding 6 and the secondary windings 7, 8, as well as a voltage-controlling switch 9, a filament resistance 10, and a milliampermeter 11. Both the transformers 3, 4, 5 and 6, 7, 8 are arranged in such a way—as can be seen from the drawing—that their primary windings 3, 6 are connected to the power-supply 14. A basic voltage is produced thereby in the windings 4, 5 of the high-voltage transformer, which is applied to the X-ray tube 1. The adjustable transformer 6, 7, 8 produces an additional voltage of variable value and positive or negative polarity, according to the position of switch 9. This additional voltage is connected to the basic voltage produced in the windings 4, 5 and will either raise or reduce this basic voltage, whereby the operating voltage of the tube 1 can be altered according to requirement.

By application of the idea of my invention 25 there is made full use of the effect of the X-ray unit A. The transformer A produces the constant basic voltage for the tube 1, so that this transformer always operates with the effect for which it was laid out. That is why it works with highest efficiency. For control of the anode-voltage at the tube 1 draw additional voltage from the adjustable transformer, which additional voltage is conducted by way of the cables 12 and 13 to the secondary windings of the transformer of unit A. In that manner the efficiency of the X-ray unit A is raised without increasing its weight. The idea of my invention renders the generally used primary control (reducing of the primary voltage or additional connecting of primary windings) superfluous, and with it the larger dimensions of the transformer involved in it. Besides reducing the weight of the X-ray unit, this means also saving of raw-material, as the controlling devices only need dimensions for weak secondary current.

In the embodiment shown by way of example both the feeding cables 12 and 13 are to be laid out for half the controlling voltage. All the wires connecting A and B can be placed therefore, together in a flexible hose 16.

From the foregoing description it will be clear to those skilled in the art that practical execution of the invention admits of variations of structure that would not go beyond the compass of my invention. It is to be understood,

therefore, that the embodiment of the invention described and shown is given by way of illustration only and not as a limitation of the scope of my invention.

I claim:

1. In an X-ray apparatus a voltage source for supplying the plate voltage of the X-ray tube, comprising a high voltage transformer for producing a basic plate voltage and an auxiliary transformer for producing a regulating voltage to vary the plate voltage, said auxiliary transformer being connected in series with the secondary side of said high voltage transformer so that the voltage supplied by said auxiliary transformer is added vectorially to the voltage supplied by said high voltage transformer.

2. In an X-ray apparatus a voltage source for supplying the plate voltage of the X-ray tube, comprising a high voltage transformer for producing an invariable basic plate voltage and an auxiliary transformer for producing a regulating voltage to vary the plate voltage, said auxiliary transformer being connected in series with the secondary side of said high voltage transformer so that the voltage supplied by said auxiliary transformer is added vectorially to the invariable voltage supplied by said high voltage transformer.

3. In an X-ray apparatus a voltage source for supplying the plate voltage of the X-ray tube, comprising a high voltage transformer having a secondary winding divided into two parts for producing a basic plate voltage and an auxiliary transformer for producing a regulating voltage to vary the plate voltage, said auxiliary transformer being connected with the separating points of said two parts of said secondary winding of said high voltage transformer and thereby in series with said secondary winding of said high voltage transformer so that the voltage supplied by said auxiliary transformer is added vectorially to the voltage supplied by said high voltage transformer.

4. In an X-ray apparatus a voltage source for supplying the plate voltage of the X-ray tube, comprising a high voltage transformer for producing a basic plate voltage and a variable transformer for producing a regulating voltage to vary the plate voltage, said variable transformer being connected in series with the secondary side of said high voltage transformer so that the voltage supplied by said variable transformer is added vectorially to the voltage supplied by said high voltage transformer.

5. In an X-ray apparatus a voltage source for supplying the plate voltage of the X-ray tube, comprising a high voltage transformer for producing a basic plate voltage and locally separate from said high voltage transformer an auxiliary transformer for producing a regulating voltage to vary the plate voltage, said auxiliary transformer being connected in series with the secondary side of said high voltage transformer so that the voltage supplied by said auxiliary transformer is added vectorially to the voltage supplied by said high voltage transformer.

6. In an X-ray apparatus a voltage source for supplying the plate voltage of the X-ray tube, comprising a high voltage transformer for producing a basic plate voltage and locally separate

from said high voltage transformer a variable transformer for producing a regulating voltage to vary the plate voltage, said variable transformer being connected in series with the secondary side of said high voltage transformer so that the voltage supplied by said variable transformer is added vectorially to the voltage supplied by said high voltage transformer.

7. In an X-ray apparatus a voltage source for supplying the plate voltage of the X-ray tube, comprising a high voltage transformer for producing a basic plate voltage and an auxiliary transformer for producing a regulating voltage to vary the plate voltage, said auxiliary transformer being regulatable at its secondary side, the latter being connected in series with the secondary side of said high voltage transformer.

8. In an X-ray apparatus a voltage source for supplying the plate voltage of the X-ray tube, comprising a high voltage transformer having a secondary winding divided into two parts for producing a basic plate voltage and an auxiliary transformer for producing a regulating voltage to vary the plate voltage, said auxiliary transformer being regulatable at its secondary side, the latter being connected with the separating points of said two parts of said secondary winding of said high voltage transformer and thereby in series with said secondary winding of said high voltage transformer so that the voltage supplied by said auxiliary transformer is added vectorially to the voltage supplied by said high voltage transformer.

9. In an X-ray apparatus a voltage source for supplying the plate voltage of the X-ray tube, comprising a high voltage transformer for producing a basic plate voltage and locally separate from said high voltage transformer an auxiliary transformer for producing a regulating voltage to vary the plate voltage, said auxiliary transformer being regulatable at its secondary side, the latter being connected in series with the secondary side of said high voltage transformer so that the voltage supplied by said auxiliary transformer is added vectorially to the voltage supplied by said high voltage transformer.
